AIR CIRCULATING DEVICE

Francis C. Kilb, Larchmont, N. Y.

Application May 9, 1936, Serial No. 78,821

13 Claims. (Cl. 98—94)

My invention relates to air circulating devices, and more particularly to devices of this character which effect circulation of air in room spaces; such, for example, as a window-mounted ventilator having a fan or blower arranged therein and operating to introduce a stream of fresh air into the room space through an air outlet opening in the front of the ventilator casing.

It will be appreciated that, as devices of the above type are usually installed in spaces occupied by people, appearance and neatness are extremely important factors to be considered in their design. As the devices are operated by all types of individuals, dependability in operation is also important. Furthermore, low cost of manufacturing and assembling, and low cost and ease of servicing, are also necessary for the commercial success of the device.

Devices of this type are usually provided with louvers in their air outlet openings which serve to direct the air flowing therefrom to desired portions of the room and/or serve to close the air outlet openings. The louvers should operate easily and simply and remain in any desired position; and they should not be mounted in the unit in such a manner as to produce a detrimental effect on the external appearance of the unit; but, on the other hand, should be mounted in a manner to add to its external appearance. Heretofore, louvers have been pivoted directly to the sides defining the air outlet opening; however, the assembly of such a construction is of necessity a relatively long and tedious operation, and therefore is relatively expensive. It has also been proposed to pivotally mount the louvers in a separate frame and attach the frame to the casing; but structures of this type, heretofore known to me, are objectionable either because it is extremely difficult to repeatedly position properly the louvers in the air outlet opening, or because time-consuming and expensive operations are required in properly positioning the frame with respect to such opening; and also because, after such a frame is mounted in the opening, it is still visible from the exterior of the device and therefore detracts materially from its appearance.

My invention has for a broad object to provide an air circulating device for use in room spaces, which is of improved construction and arrangement of parts.

Further and more specific objects of my invention are to provide efficient louver means for an air circulating device which can be easily manufactured, assembled, and serviced, and at a low cost; which can be quickly and accurately posi-

tioned with respect to the air outlet opening; and one which, in its preferred form, presents a neat appearance from the exterior of the device.

Without imposing any limitation on the invention in its broader aspects, a still further object is to provide an improved form of louver construction for air circulating devices which can be readily adjusted to direct the air to different desired portions of the room and which is effectively retained at any desired adjusted position.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a vertical transverse sectional view of a window-mounted ventilator constructed in accordance with the present invention, the view being taken on the line 1—1 of Fig. 2;

Fig. 2 is a front elevation of the device shown in Fig. 1, drawn on a reduced scale;

Fig. 3 is a perspective view showing the inside of a portion of the front cover of the ventilator casing with a unitary louver frame assembly removed from the cover to illustrate its construction and mode of assembly;

Fig. 4 is a fragmentary horizontal plan sectional view of the front cover of the ventilator casing with the louver frame assembly mounted therein, the line of the section being indicated by the line 4—4 of Fig. 2;

Fig. 5 is a perspective view of the unitary louver frame assembly showing the side thereof opposite to that shown in Fig. 3;

Fig. 6 is a perspective view of the louver frame shown in Fig. 5 with the louver plates omitted;

Fig. 7 is a detail assembly view showing the construction of the louver plates and the pivot rod therefor;

Fig. 8 is an enlarged detail assembly view showing more clearly the unitary link assembly for operating the louver plates in unison; and

Fig. 9 is a view similar to Fig. 6, but showing a modified form of louver frame.

In the accompanying drawings, I have shown my invention as incorporated in a window ventilator comprising a casing structure 10 suitably supported by a window sill 11 and arranged within the opening defined by a partially raised sash 12 and the sill 11. The ventilator casing is arranged midway between window jambs 13, as shown, and suitable filler blocks 14 serve to close

50

55

the spaces between the ends of the ventilator casing 10 and the jambs 13. The casing 10 comprises a front wall 15 having an air outlet 16; a rear wall 17 having an air inlet 18; a bottom wall 19 secured to the window sill 11; a top wall 20 having a sealing engagement with the lower rail 21 of the window sash 12, and having a louver-controlled air outlet 22 in the portion thereof extending into the room; and end walls 23. The outlet 16 extends for substantially the full length of the front wall 15 and is divided in its center by a vertical strip 24 into outlet openings 25 and 25a of similar size and shape. The inlet opening 18 extends preferably for the full length and height of the rear wall 17 and rigid louvers 26 are provided on the rear wall for preventing the entrance into the ventilator of snow and rain. A suitable removable filter 27 is arranged inside of the ventilator and is disposed across the inlet opening 18 to remove dust particles and the like from the incoming air.

For the purposes of initial assembly, and of removal, repair, and replacement, the casing 10 is divided preferably into two parts 30 and 31. The part 30 is fixedly mounted in the window opening and consists of the bottom wall 19, the rear wall 17, rear wall parts 32 of the end walls 23, and rear wall part 33 of the top wall 20, the latter being hinged at the back as indicated at 34 to permit insertion and removal of the filter 27. The part 31 is readily removable as a unit from the part 30 and comprises the front wall 15, front wall parts 35 of the end walls 23, and front wall part 36 of the top wall 20. The part 31 may be appropriately referred to as the removable front cover unit and the part 30 as the fixedly mounted base unit.

A partition 37 extends longitudinally of the casing 10 for the full length and height thereof and divides the latter into a rear inlet chamber 38 communicating with the inlet 18 and an outlet chamber 39 communicating with the outlet 16 and outlet 22. The partition 37 is provided in its upper part with an opening 40 connecting the chambers 38 and 39.

Arranged within the inlet chamber 38 is a removably mounted motor-driven blower unit 41 having an inlet 42 communicating with the inlet chamber 38 and an outlet 43 communicating with the outlet chamber 39 through the opening 40 in the partition 37. A suitable damper 44 extends lengthwise of the casing in the outlet chamber 39 and is pivotally supported at its upper end as indicated at 45. The damper in one position provides for the closing of communication between the inlet and outlet chambers 38 and 39; and, when in another position, forms a part of a tortuous sound deadening passage 46 connecting the opening 40 and the outlets 16 and 22. The open position of the damper 44 is the position shown in Fig. 1 of the drawings.

As stated, the outlet 16 is divided by the strip 24 into the openings 25 and 25a. From an examination of Figs. 2, 3 and 4, it will be seen that the opening 25 is defined by top and bottom edge portions 50 and 51 and by vertical side edge portions 52 and 53. Likewise, the opening 25a is defined by top and bottom edge portions 50a and 51a and by vertical side edge portions 52a and 53a. The top edge portions 50 and 50a of the openings 25 and 25a, respectively, are in the same horizontal plane. Likewise, the bottom edge portions 51 and 51a of the openings 25 and

25a are in the same horizontal plane. The edge portions 52, 53, 52a and 53a of the openings 25 and 25a are arranged in parallel relation, as shown, with the edge portions 53 and 52a forming the vertical sides of the dividing strip 24.

In accordance with the present invention, I have provided an improved form of louver means which is carried by the front wall 15 and forms a part of the removable cover unit 31. The louver means is mounted in the openings 25 and 25a forming the outlet 16. This louver means is preferably so constructed as to direct the air flowing from the casing 10 to different desired portions of the room, and also serves to close said outlet 16, and comprises a frame 55 preferably formed integral with the front wall 15, and a removable louver frame assembly 56 detachably secured to the inside of the wall 16.

From an examination of Fig. 3, it will be seen that the frame 55 comprises sub-frames 57 and 57a bounding the outlet openings 25a respectively. The sub-frame 57 comprises flanges 59 and 60 extending inwardly from the top and bottom edge portions 50 and 51, respectively, and flanges 61 and 62 extending inwardly from the side edge portions 52 and 53, respectively. The flanges 59, 60, 61 and 62 are formed integral with the front wall 15 of the casing and bound the outlet opening 25.

Likewise, the sub-frame 57a comprises inwardly extending top and bottom flanges 59a and 60a, and vertical side flanges 61a and 62a which are formed integral with the front of the casing and bound the outlet opening 25a. A plurality of series of inwardly opening notches 63, 64, 63a and 64a are formed in the vertical side flanges 61, 62, 61a and 62a for a purpose which will presently appear. The notches 63, 64, 63a and 64a forming each series are in horizontal alignment.

The louver frame assembly 56 is formed as a unit and is secured removably to the inside of the front wall 15 by suitable screws 65 threaded in openings in brackets 66 suitably fixed, for example by spot welding, to the front wall 15. The louver frame assembly 56 comprises a main frame 67 and louver plates 68 pivotally mounted in the main frame on horizontally-extending pivot rods 69.

In the construction shown in Figs. 1, 3, 4, 5 and 6, the main frame 67 comprises a top member 70, a bottom member 71 in parallel spaced relation, end members 72 and 73, and closely spaced intermediate members 74 and 75 connecting the mid portions of the top and bottom members 70 and 71 to thereby form a rigid rectangular structure. The top member 70 is provided with an outwardly-extending flange 76 of predetermined width. Likewise, the bottom member 71 is provided with an outwardly extending flange 77 of the same predetermined width as the flange 76. The end members 72 and 73 and intermediate members 74 and 75 are provided with outwardly-extending flanges 78, 79, 80 and 81, respectively, and of the same predetermined width as the flanges 76 and 77. The flanges 76, 77, 78, 79, 80 and 81 are formed integral with and extend outwardly from the inside edges of the top member, bottom member, end members, and the intermediate members, respectively; and these flanges define a pair of hollow sub-frames 82 and 82a which are of the same configuration as the frames 57 and 57a on the front wall of the casing, but are slightly larger in dimensions.

As can be readily seen from an examination

of Figs. 1 and 4, when the louver frame assembly is in position against the inside of the front wall 15, the sub-frames 82 and 82a embrace and fit snugly the sub-frames 57 and 57a, respectively, of the casing. In assembled position, the outermost edges of the flanges 78, 79, 80 and 81 preferably engage the inside surface of the front wall of the casing; and, as the flanges are of the same predetermined width, they serve to assure a predetermined position of the louver frame assembly with respect to such front wall and the openings 25 and 25a. As the flanges forming the sub-frames 82 and 82a of the louver frame fit and positively engage the exterior surfaces of the corresponding flanges forming the sub-frames 57 and 57a on the casing, the louver frame is positively positioned with respect to the outlet openings 25 and 25a and is prevented from displacement in directions parallel to the front 20 of the casing and the plane of the outlet openings 25 and 25a. The screws 65 passing through the end members 72 and 73 and through screw-threaded openings in the brackets 66, serve to positively hold the louver frame assembly in position against the inside surface of the front wall 15.

As stated, the louver frame assembly 56 also comprises a plurality of louvers 68 pivotally mounted on rods 69, said louvers 68 being arranged in parallel relation to one another within each of the sub-frames 82 and 82a, and the louvers of one sub-frame are arranged coaxial with corresponding louvers in the other sub-frame. Each of the pivot rods 69 extends horizontally through aligned openings in the end and intermediate flanges 78, 79, 80 and 81 and passes through and is suitably secured to correspondingly positioned louvers in the sub-frames, so that corresponding louvers in the sub-frames 40 move about the same axis and the louvers of each sub-frame move about parallel axes.

When the louver frame assembly is in place against the inside of the front wall 15, the louver plates are disposed within the sub-frames 57 and 57a adjacent the openings 25 and 25a, with just enough clearance between the ends of the plates and the adjacent flanges to permit pivotal movement of the louvers. Sufficient clearance is provided between the ends of the louver plates 50 and the sides of the sub-frames 82 and 82a to permit the location of the side flanges of the sub-frames 57 and 57a between the ends of the louvers and the sides of the sub-frames 82 and 82a. The aligned notches 63, 64, 63a and 64a 55 receive the intervening portions of the pivot rods 69 so as to permit the proper positioning of the louvers and frame with respect to the openings 25 and 25a.

Each of the louvers 68 is provided at its end 60 adjacent the vertical dividing strip 24 with an inwardly extending flange 85. The flanges 85 of all of the louvers are connected together for operation in unison by a link assembly, indicated in general by the reference character 86 (see Fig. 8). The link assembly comprises a pair of spaced side links 87 and 88 connected together by cross pins 89 and 90, the latter being suitably spot welded to the side links. The side links 87 and 88 are provided with outwardly-turned end 70 portions 91 which are adapted to fit within openings provided in the outer end of the flanges 85 of the top and bottom louvers of each of the sub-frames 82 and 82a. The cross pins 89 and 90 extend beyond the links 87 and 88 and are adapted to fit within openings provided in the outer 75

portions of the flanges 85 of the intermediate louvers of the sub-frames.

An operating lever 93 extends through a slot 94 provided in the dividing strip 24 in the front wall of the casing, and is suitably pivoted on the intermediate portion of one of the pivot rods 69, as can be seen from an examination of Fig. 5. The inner end of this operating lever is forked, as indicated at 95, and engages the connecting pin 89 of the link assembly 86. The opposite end of the operating lever is provided with a knurled portion 96 which can be grasped by the hand from the exterior of the casing for moving the link assembly up or down and, consequently, the louvers in either direction or to closed position.

An arcuate-shaped spring member 100 is arranged substantially concentric to the arc of movement of the forked end 95 of the operating lever 93 and engages the inner end of such lever. The ends of the spring member 100 are anchored by screws 101 suitably threaded in cross-pieces 102 and 103 secured by spot welding to the intermediate members 74 and 75 of the louver frame. The arcuate-shape spring member 100 is formed on its concave side with notches 104, 105 and 106 in which the forked end 95 of the lever is adapted to fit. By reason of this construction, the member 100 serves as a spring-pressed brake for the operating lever 93 to prevent accidental movement of the lever and louvers, and when the forked end fits within one of the notches in the member 100, the lever is more firmly held. The notches are suitably positioned to afford this extra precaution against accidental movement at the two extreme positions and at the mid or closed positions of the lever and louvers. In Fig. 1 of the drawings, one extreme open position is shown in full lines, and the closed position of the louvers and lever is shown in dotted lines.

From the above, it will be readily seen that I have provided an air circulating device which is of improved construction and arrangement of parts. As the louver frame assembly is in the form of a separately assembled unit having the louvers properly positioned and mounted therein previous to attachment to the casing, and having spacing flanges of fixed dimensions which are constructed to embrace snugly cooperating flanges on the casing, and which engage positively the inside surface of the front wall of the casing; the louvers may be at all times properly and quickly positioned with respect to their respective outlet openings and with a minimum requirement of time. As the inwardly extending flanges of the casing fit within the outwardly extending flanges of the louver frame assembly, no sharp edges or rough surfaces can be seen from the front of the casing. Therefore, the outlet openings with the louvers properly positioned therein, present a neat and pleasing appearance. Furthermore, the particular mounting of the louvers in the frame with the operating link assembly, operating lever and arcuate-shape spring, provide a louver construction for air circulating devices which can be readily and easily adjusted to direct the air to different desired portions of the room or to close the opening and which effectively retain the louvers in any desired adjusted position.

In Fig. 9 of the drawings, I have shown a louver frame which is manufactured in a different manner from the previously described construction. The modified louver frame is indicated at 110 and comprises an integral one-piece unit, having sub-frames 111 and 112 formed by flanges 113 and 75

which are stamped out of a single piece of metal. The louver frame shown in Fig. 9 is formed of elements which function identically with the elements of the one shown in Fig. 6, the only difference being that the one shown in Fig. 6 is formed of angle pieces spot welded together, and the one shown in Fig. 9 is a single stamping. The construction of Fig. 9 may be less expensive than the construction previously described, should the units be made in sufficiently large quantities to justify the initial cost of the dies for stamping.

What I claim and desire to secure by Letters Patent of the United States is:

1. An air circulating device for use in room spaces, comprising walls defining a casing; one wall of said casing having an air opening therein; flanges extending inwardly of the casing from the edges defining said opening; a louver frame arranged within said casing adjacent said opening and behind said flanges so that the frame is concealed by the flanges; and louvers carried by said frame and extending across said opening for controlling the flow of air through said opening.
2. An air circulating device for use in room spaces, comprising a casing including a wall structure, one wall of which is provided with an opening; a louver frame arranged inside of said casing and adjacent the sides of said opening and including outwardly directed flanges engaging at their outer edges the inside surface of said one wall; louvers carried by said flanges and extending across said opening; and flanges extending inwardly of said casing from the defining edges of said opening and overlapping and concealing the flanges of said louver frame.
3. An air circulating device for use in room spaces, comprising a casing including a wall structure, one wall of which is provided with an opening; a louver frame arranged inside of said casing; louvers pivotally mounted at their ends to said frame and extending across said opening; flanges extending inwardly from the defining edges of said opening and concealing said louver frame; said flanges having inwardly-opening notches receiving the pivotal mountings for said louvers.
4. An air circulating device for use in room spaces, comprising a casing including a wall structure, one wall of which is provided with an opening; positioning flanges extending inwardly of the casing from the inside defining edges of the opening; and a louver frame assembly arranged interiorly of said casing and having outwardly extending flanges engaging the surfaces of said casing flanges which are remote from the opening so as to position the louver frame assembly positively with respect to said opening.
5. An air circulating device for use in room spaces, comprising a casing including a wall structure, one wall of which is provided with an opening; flanges rigid with said wall and projecting inwardly into the casing from opposite edges of said opening; a unitary louver structure arranged within said casing and adjacent said opening and including a frame member conforming substantially to the contour of said opening; said frame member including opposite frame elements located respectively on the sides of said flanges which are remote from said opening; and louver plates pivoted in said frame elements and extending across said opening; said louver frame having parts projecting outwardly therefrom into engagement with the interior surfaces of said wall.
6. An air circulating device for use in room spaces, comprising a casing including a wall struc-

ture, one wall of which is provided with an opening; flanges rigid with said wall and projecting inwardly into the casing from opposite edges of said opening; a unitary louver structure arranged within said casing and adjacent said opening and including a frame member conforming substantially to the contour of said opening; said frame member including opposite frame elements located respectively on the sides of said flanges which are remote from said opening; and louver plates pivoted in said frame elements and extending across said opening; said louver frame having parts projecting outwardly therefrom into engagement with the interior surfaces of said wall and engaging at their inner side surfaces the surfaces of said flanges which are remote from said opening.

7. An air circulating device for use in room spaces comprising walls defining a casing structure; one of said walls having an air opening therein; frame means rigid with said casing and comprising positioning flange members extending interiorly of the casing from the inside edge portions of said opening and being disposed at opposite sides of the opening; and a louver frame assembly secured to the casing at the inside thereof and comprising a louver frame member similar in shape to said casing frame means and slightly larger in dimensions, and a plurality of louver plates pivotally mounted at their opposite ends to the louver frame member; said louver frame member including outwardly extending portions receiving the pivotal mountings for the louver plates and being arranged at the outside of and engaging the sides of said flange members, and abutting the inside surfaces of the casing.

8. An air circulating device for use in room spaces, comprising walls defining a casing structure; one of said walls having an air opening therein; frame means rigid with said casing and comprising positioning flange members extending interiorly of the casing from the inside edge portions of said opening and being disposed at opposite sides of the opening; and a louver frame assembly secured to the casing at the inside thereof and comprising a louver frame member similar in shape to said casing frame means and slightly larger in dimensions, and a plurality of louver plates pivotally mounted at their opposite ends to the louver frame member; said louver frame member including outwardly extending portions receiving the pivotal mountings for the louver plates and being arranged at the outside of and engaging the sides of said flange members.

9. An air circulating device for use in room spaces, comprising walls defining a casing structure; one of said walls having an air outlet opening therein having pairs of opposed sides; casing frame means comprising positioning flanges formed integral with said one casing wall and extending interiorly of the casing from the inside edges of said opening, there being a flange at each side of the opening and extending for the full length thereof, and the flanges being arranged in planes normal to the plane of the outlet opening; one pair of the oppositely disposed flanges having alined notches formed therein and opening inwardly of said casing; and a louver frame assembly secured to the casing at the inside thereof and comprising a frame member similar in shape to the casing frame means and slightly larger in dimensions, a plurality of louver plates, and means for pivotally mounting the plates at their opposite ends to the louver frame member; said louver frame member including outwardly

extending portions arranged at the opposite side of and engaging the sides of the casing flanges and having their outermost edges abutting the inside surfaces of the casing whereby the louver frame, with the louver plates mounted therein, is positively positioned in directions both lateral and normal to the plane of the outlet opening; said pivotal mounting means comprising pivot rods extending from the ends of the louver plates through the alined notches in the casing frame flanges and being secured at their outer ends to the outwardly extending portions of the louver frame.

10. An air circulating device for use in room spaces, comprising a casing including a wall having an air outlet opening; flanges extending interiorly of the casing from said wall and bounding said outlet opening to provide a frame rigid with the wall and at the inside of the opening; said flanges having a plurality of relatively deep inwardly opening notches formed therein and disposed at opposite sides of the opening with each of the notches being in alinement with a corresponding notch on the opposite side of the opening; a louver frame having an opening of substantially the same configuration as said outlet opening and having slightly larger dimensions; said louver frame including outwardly extending flanges formed rigid with the louver frame and bounding the opening therein; said louver frame flanges embracing and fitting snugly about the casing flanges and engaging at their outer edges the inside surfaces of the casing; pivot rods extending across the openings and through said alined notches and secured at their opposite ends in the louver frame flanges; a plurality of louver plates arranged within the space defined by the casing flanges and extending across such space from one side to the opposite side thereof and each plate being pivotally mounted on one of the pivot rods; and means for securing the louver frame to the casing wall.

11. An air circulating device for use in room spaces, comprising a casing having a pair of rectangular-shaped openings of substantially the same dimensions and being disposed in side-by-side relation with a relatively thin strip of casing structure therebetween and with one pair of the opposed sides of one opening arranged in the same planes as the corresponding sides of the other opening and with the other pair of opposed sides of said one opening disposed parallel to the corresponding sides of the other opening; flanges formed integral with said casing and extending inwardly from each side edge of each of the openings to provide a pair of rectangular frames coextensive with their respective openings at the inside thereof; a louver frame assembly comprising a frame structure including outwardly extending flanges disposed in the form of a pair of rectangles of the same shape and

slightly larger than the aforementioned rectangular frames; said frame structure being arranged at the inside of the casing with it outwardly extending flanges embracing and fitting snugly about the rectangular frames on the casing and having the outer edges of its outwardly extending flanges engaging the inside of the casing to properly position the louver frame structure with respect to the outlet openings; a plurality of parallel louvers arranged across each of the openings; pivot pins pivotally connecting the ends of the louvers with the flanges on the frame structure; and said flanges on the casing being provided with inwardly opening notches receiving the pivot pins.

15. 12. A removable unitary louver frame assembly of the type which is adapted to be installed in an air circulating casing, comprising a body member having a pair of rectangular-shaped openings having substantially the same dimensions and being disposed in side-by-side relation, with one pair of the opposed sides of one of the openings arranged in the same planes as the corresponding sides of the other opening and with the remaining sides of the openings arranged in parallel relation to one another; flanges extending outwardly from one side of the body member at each side edge of each of the openings to provide a pair of rectangular sub-frames coextensive with their respective openings; a plurality of parallel equally spaced pivot rods extending across both openings and connected to the flanges of the sub-frames; and louver plates pivotally mounted on the rods within each of the openings.

35. 13. An air circulating device for use in room spaces, comprising a casing having an opening therein; a plurality of parallel louvers extending across the opening and pivotally connected at their ends to opposite defining edges of the opening so as to move about parallel axes; a flange member extending from each of the louvers inwardly from the casing at one side of the opening; link means connecting the flange members for moving the louvers in unison; an operating pin connected to the flange of one of the louvers and arranged parallel to its axis of movement; an operating lever mounted for pivotal movement about an axis parallel to said pin and having a slotted end engaging said pin; and an arcuate-shaped spring member disposed substantially concentric with the axis of movement of the slotted end of the lever and being in engagement with the latter; said spring member being anchored at its ends at opposite sides of the slotted end of the lever and having spaced-apart notch portions therein, in which the slotted end of the lever is adapted to fit and be resiliently held thereby when at predetermined positions.

60. FRANCIS C. KILB.
